UNITED STATES PATENT OFFICE.

JESSE HARRIS, OF RENSSELAER, NEW YORK.

ELECTRIC METER.

992,768.

Specification of Letters Patent. Patented May 23, 1911.

Application filed September 26, 1906. Serial No. 336,317.

To all whom it may concern:

Be it known that I, JESSE HARRIS, a citizen of the United States, residing at Rensselaer, in the county of Rensselaer and State of New York, have invented a certain new and useful Improvement in Electric Meters, of which the following is a full, clear, concise, and exact description, reference being had to the accompanying drawings, forming a part of this specification.

My invention relates to electric meters, and is of particular service in connection with indicating instruments, though I do not wish to be limited in all embodiments 15 of my invention to indicating instruments.

My invention has a number of objects in view, among which is the provision of a high torque, a construction of the moving element that will make it light, and, particularly with reference to indicating instruments, the provision of improved means whereby a long even scale or a scale of selected graduations may be produced and the instrument may be made dead beat.

I am aware that it is old to produce even scales, or scales of selected gradation, but this result has been gained at considerable cost, because it has been customary to machine the pole pieces especially or to add 20 pole pieces so shaped as to produce the result intended. I accomplish this result by so shaping the magnet metal in forming machines that it may be used without the necessity of having it machined. To this 25 end, I desirably form the magnet into a loop that is nearly closed, the ends of the magnet lying in different planes, so that the armature of the meter may occupy a plane intermediate of the polar planes and substantially parallel therewith. The polar faces of the magnet are desirably separated a distance sufficient to permit the passage of the armature shaft between the same, which feature of construction avoids the necessity of 30 causing the ends of the magnet to overlap and the provision of shaft holes through the overlapping ends of the magnet, though I do not wish to be limited to my preferred construction. In order to reduce the reluctance between the magnet poles, and to produce the desired operation of the pointer, or index, I interpose a normally stationary soft iron element between said poles, whereby an enhancement of the torque upon the armature is secured. This soft iron element, by its 35 shape and position, may be used in determin-

ing the character of the scale. If it is desired to have the scale uniform, this soft iron piece may have one construction and position. If, on the other hand, it should be desired 40 to have the normally active portion of the scale very open as compared with the balance of the scale, whereby this open portion may be easily read, the position of the iron element may be changed or the shape of the 45 iron element may be changed, or both change in position and shape may be effected for the purpose. I have produced a scale whose graduations increase and decrease by making the soft iron element in the form of a 50 ring of equal radial cross-section throughout and placing the portion of the ring controlling the open part of the scale near the magnet.

I produce a light moving element for indicating instruments by a peculiar formation of the closed conductor member of the damping device in combination with an armature coil mounted upon the said closed conductor, the arrangement being such that 55 the major portion of the closed conductor lies upon one side of the shaft while the moving coil lies upon the other side of the shaft, whereby the weight of the moving element is symmetrically disposed with respect to the shaft, my improved magnet arrangement enabling me to make the moving element of very light construction.

The magnet that I employ acts as a damping magnet in its operation upon the closed 60 conductor.

The instrument herein shown and described is dead-beat.

I will explain my invention more fully by reference to the accompanying drawing, 65 showing the preferred embodiment thereof, in which—

Figure 1 is a view in elevation of the instrument. Fig. 2 is a side elevation. Fig. 3 is a view of part of the mechanism as it 70 would appear with the upper pole of the permanent magnet removed. Fig. 4 indicates one modification. Fig. 5 indicates another modification.

Like parts are indicated by similar characters of reference throughout the different figures.

I have not deemed it necessary to show the meter casing nor the circuit connections of the meter.

The meter illustrated happens to be a volt 75 meter, though the invention is not to be

105

110

limited to volt meters, nor in all embodiments to indicating instruments.

The permanent magnet *a* is desirably highly magnetized, though the magnets should be aged, of course, and is preferably formed to constitute almost an entirely closed loop, whose free polar ends *b* and *c* are so related as to permit passage of an armature shaft or arbor *d* between the same.

10 These poles desirably occupy different planes, so that a moving element of the instrument (in an indicating instrument, the armature and closed conductor damping portion) may be disposed in a plane intermediate of these planes and substantially parallel therewith. In the embodiment of the invention shown, the moving element includes a closed conductor *e* and an armature coil *f*, desirably mounted upon a continuation *g* of the closed conductor, which continuation, with the balance of the conductor, constitutes a damping device. The coil *f* thus has a metallic foundation or mounting, which also acts as a damping element. The 25 armature shaft or arbor *d* supports the coil and the closed conductor, the continuation *g* and the coil *f* upon one side of the shaft approximating in weight a sector-shaped portion of the closed conductor upon the other 30 side of the shaft, whereby a balanced construction is secured.

It will be seen that the pole *c* is adapted to generate one set of eddy currents and the other pole *b* is adapted to generate another set of eddy currents, because these poles are not superposed or sufficiently coincident to produce but one set of eddy currents.

I desirably interpose a normally stationary ring segment *h*, made of soft iron, between the poles of the permanent magnet, this ring of soft iron lying in a plane parallel to the polar planes. The armature winding *f* surrounds the ring *h*, which preferably passes through the bore of said winding. 45 The ring *h* thus tends to close the magnetic circuit of the permanent magnet, thereby strengthening the field in which the armature coil may move.

The ring piece *h* of soft iron acts as a 50 path for the magnetic flux and conducts said flux in proportion to its cross-section and proximity to the polar faces of the permanent magnet. The air gap between the poles of the permanent magnet offers a resistance to the magnetic flux. The ring being inserted in this space, lessens this resistance and deflects and guides said flux, as predetermined by its shape and the position in which it is placed.

60 The torque is the product of the flux produced in the moving coil and that of the permanent magnet cut by said moving coil for each position it takes. With a regular increase of current in the moving coil and 65 an even magnetic flux from the permanent

magnet, throughout the range of movement of said moving coil, a regular and evenly spaced scale would result.

The object of the tongue enlargement of ring *h*, when employed, is to lessen the magnetic resistance of the air gap at that portion of the swing of the moving coil, thus increasing the flux at that point, and by so doing increasing the torque and widening the spaces in the scale for each regular increase of current in the moving coil. Two ways are thus provided for defining the permanent magnet flux, in certain portions of the swing of the moving coil. Both ways have to do with modifying the air gap between the poles and ring. In Fig. 4 the tongue *f* is provided upon ring *h*, and in Fig. 5 the air gap is shortened by tilting the ring *h* toward the pole of the magnet. Both methods result in increased scale spaces 85 corresponding to the bunching of the magnetic flux. In Fig. 4 the changes would be more abrupt, while in Fig. 5 the change from close to wider lines or spaces would be gradual.

If it is desired to have the scale evenly graduated throughout, the ring may be of uniform radial cross-section throughout and may be placed in a plane substantially parallel with the planes of the poles of the permanent magnet. If it is desired to have the scale gradually increase and then gradually decrease, this same ring, instead of lying in a plane parallel with the polar planes of the permanent magnet, may be inclined as indicated in Fig. 5, the portion of the ring controlling the open part of the scale being nearest the permanent magnet. If it is desired to have the first and last sections of the scale with closer graduations than an intermediate portion of the scale, the iron ring may be provided with the projection *f* as indicated in Fig. 4 extending between the radii that mark the limits of the central portion of the scale. Of course, if some other portion of the scale is to be more open than the balance, the projection upon the ring is correspondingly disposed. In other words, I make the ring of such an area, per unit of length that is traversed by the moving coil, that the portions offered to the magnetic flux are, so to speak, a duplicate of or proportional to the scale desired. The scale as illustrated in Fig. 4 is of use in relation to volt meters employed in connection with 115 110 volt circuits, as the portion of the scale between 90 volts and 130 volts (in a 150 volt scale) may be made very prominent, so that any changes may be easily manifested in the 120 normally active part of the scale.

It will be seen that by means of the non-superposed pole arrangement and the inclusion of the ring *h* in the magnetic circuit between the poles, the reluctance of the magnetic circuit is one almost entirely to 130

the air gaps. The soft iron element *h* is desirably of such section that it will carry freely substantially all the lines of force in the permanent magnet, the lines of force 5 where they thread the air gaps being alone available for the operation of the instrument.

By means of my new construction, no machine work or shaping of pole pieces is 10 necessary, the permanent magnet being merely bent into its shape by a shaping machine, it not being necessary to machine it thereafter, as it is capable of effecting an equal distribution of magnetic flux in the 15 shape in which it leaves the forming machine.

In other instruments hitherto devised, it is necessary to have specially shaped pole pieces to get the desired scale arrangement.

20 In my invention the instrument winding is preferably placed in one gap and the damping element is preferably placed in the other gap, whereby the damping effect is increased.

25 In the device of my invention substantially the entire damping element is threaded by the magnetic flux and the damping circuit is very short, whereby weight is not only eliminated, but the effectiveness of the 30 eddy currents is increased.

In the device of my invention, the instrument may be non-symmetrically arranged with respect to its axis of rotation, whereby an increased leverage is secured without an 35 increase of weight, the pointer or index and the winding being balanced by means of the damping plate, a characteristic of considerable importance in connection with an instrument designed to answer quickly to any 40 changes of load in the electrical circuit.

In the case of indicating instruments, a suitable coil spring construction *i* may be employed for swinging the index to zero (0) and against which the torque of the 45 instrument is exerted, in order that the index or pointer may indicate the value being measured.

The clip *y* is added merely for adjusting the balance of the structure, comprising the closed conductor and the pointer. 50

It is obvious that changes may readily be made in the device of my invention as shown in its preferred embodiment, without departing from the spirit of the invention, and I do not, therefore, wish to be limited to 55 the precise construction shown, but,

Having thus described my invention, I claim as new and desire to secure by Letters Patent:

1. An electric meter including a magnet 60 having polar portions which lie in different planes that are substantially parallel with the plane of movement of the moving element of the meter, an iron element interposed between the polar planes and located 65 opposite the poles, the moving element being disposed in a plane between the polar planes and including a winding located substantially upon one side of the axis of movement of the movable element, and a closed conductor located substantially upon another side of the axis of movement of the 70 movable element.

2. An electric meter including a magnet having polar portions which lie in different 75 planes that are substantially parallel with the plane of movement of the moving element, an iron element interposed between the polar planes and located opposite the poles, the moving element being disposed in a plane between the polar planes and including a winding encircling 80 the iron element and located substantially upon one side of the axis of movement of the movable element, and a closed conductor located substantially upon another side of the 85 axis of movement of the movable element.

In witness whereof, I hereunto subscribe my name this 18th day of Sept. A. D., 1906. 90
JESSE HARRIS.
